CLAIM

The ornamental design for a storage bag as shown and described.

DESCRIPTION

FIG. 1 is a perspective view of a storage bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the storage bag where the storage bag is in a first configuration of use; and,

FIG. 10 is a perspective view of the storage bag where the storage bag is in a second configuration of use.

The thick evenly spaced broken lines in the drawings depict stitching and form no part of the claimed design. The thin evenly spaced broken lines in the drawings depict portions of the storage bag and form no part of the claimed design.

1 Claim, 10 Drawing Sheets
